UNITED STATES PATENT OFFICE.

ORRAL ORVAL BUICE, OF MONTGOMERY, ALABAMA.

DOOR FOR BOOKCASES OR THE LIKE.

SPECIFICATION forming part of Letters Patent No. 729,270, dated May 26, 1903.

Application filed May 26, 1902. Serial No. 108,958. (No model.)

To all whom it may concern:

Be it known that I, ORRAL ORVAL BUICE, a citizen of the United States, and a resident of Montgomery, in the county of Montgomery and State of Alabama, have invented a new and Improved Door for Bookcases or the Like, of which the following is a full, clear, and exact description.

The invention relates to bookcases, show-cases, and like holders; and its object is to provide a new and improved door which is simple and durable in construction, easily applied, and readily moved into a closed or open position, the door when in an open position being completely out of the way of the user of the bookcase.

The invention consists of novel features and parts and combinations of the same, as will be more fully described hereinafter and 20 then pointed out in the claims.

A practical embodiment of the invention is represented in the accompanying drawings, forming a part of this specification, in which similar characters of reference indicate corresponding parts in all the views.

Figure 1 is a rear sectional elevation of the improvement on the line 1-1 of Fig. 2. Fig. 2 is a transverse section of the same, and Fig. 3 is a perspective view of a corner of the 30 door.

The box-like body A of the bookcase, show-case, or like article is formed at the inner faces of its sides B with guideways C, extending horizontally near the top of the box-body, and the said guideways are preferably in the form of grooves formed in the sides B and having metal strips at the bottom, as plainly indicated in Fig. 1. The guideways C are engaged by pivots D, preferably in the 35 form of friction-rollers, journaled on studs secured to the sides of the door E, near the top thereof, the door when in a closed position, as shown in Figs. 1 and 2, resting with its rear face on vertical strips F, secured to the 40 inner faces of the sides B, near the front thereof.

On the upper ends of the strips F are journaled friction-rollers G for the door to rest on when moved into an open position, as indicated in dotted lines in Fig. 2, the friction-rollers G having their tops extending close to

the bottom of the guideways C, at the front ends thereof. (See Fig. 2.) Now when the door E is in a closed position, as shown in the drawings, and it is desired to open the door, 55 then the operator swings the door E outward, the door then turning on its pivots D in the front ends of the guideways C, and when the door has been moved into a horizontal position the operator pushes it backward, so that 60 the pivots D slide in the guideways C and the rear face of the door travels on the top of the friction-rollers G until the pivots D reach the rear end of the horizontal portion 65 of the guideways C. Now it will be seen that the door is now supported by the pivots D and the friction-rollers G.

In order to prevent the pivots D from binding in the guideways C, I provide the rear face of the door E at the upper corners with 70 friction-rollers H, adapted to travel on the inner faces of the sides B directly below the bottoms of the guideways C, it being understood that when the door is swung from a closed position into a horizontal position then 75 the friction-rollers H clear the friction-rollers G and their studs assume a vertical position for the peripheral faces of the friction-rollers to travel on the inner faces of the sides B.

The rear ends of the guideways C are preferably inclined upwardly and rearwardly to permit of readily engaging the pivots with the guideways and assembling the parts forming the bookcase. These upwardly-inclined portions of the guideways also serve as buffer-stops for the door when it is thrust inwardly. They practically take the place of springs or buffers for the rear edge of the door or for the pivots D when the door is in its horizontal position. They stop it effectually by 80 gravity, but not suddenly, and are sure to return the front edge into proper position to be grasped by the fingers when it is desired to close it. If the guideways terminated suddenly without these inclined ends, there would 85 be danger of breaking the pivots D by the sudden abutting of the same against the rear ends of the guideways at any time the door happened to be thrust inward too suddenly.

When it is desired to close the door, the 100 operator simply draws the door outwardly in a horizontal direction until the pivots D reach

the forward ends of the guideways C, and then the operator swings the door downward until its inner face rests against the strips F.

The arrangement described is very simple and durable in construction and permits of moving the door in an open position completely out of the way of the user of the bookcase.

Having thus described my invention, I claim as new and desire to secure by Letters Patent—

1. A bookcase or like article having side resting-strips provided with rollers in their upper ends, sides having guideways near the top, said guideways terminating in rearwardly and upwardly extending inclines, and a door adapted to rest against the resting-strips and having pivots engaging the said guideways, as set forth.
2. A bookcase or like article having side resting-strips, guideways on the sides near the top, a door adapted to rest against the resting-strips and having pivots engaging the said guideways, and rollers on the rear face of the door, adjacent to the guideways, as set forth.
3. A bookcase or like article having side resting-strips, guideways on the sides near the top, a door adapted to rest against the

resting-strips and having pivots engaging the 30 said guideways, rollers on the rear face of the door, adjacent to the guideways, and rollers journaled on the top of the resting-strips, as set forth.

4. A bookcase or like article having guide- 35 ways in the sides near the top; said guideways terminating at their inner ends in rearwardly and upwardly inclined sections; a door having pivots engaging said guideways; and supports for the front edge of the door 40 when it is in an open position as and for the purpose set forth.

5. A bookcase or like article having guide- 45 ways on its inner sides near the top, said guideways terminating in rearwardly and up- wardly inclined sections; a door having pivots engaging said guideways; rollers on the rear face of the door adjacent the guideways; and roller-supports for the front portion of the door when it is in an open position, as 50 specified and shown.

In testimony whereof I have signed my name to this specification in the presence of two subscribing witnesses.

ORRAL ORVAL BUICE.
